Continuation of application Serial No. 547,546,
June 29, 1931. This application October 6,
1933, Serial No. 692,513

4 Claims. (Cl. 164—23)

This invention relates to machines for operating upon sheet material and is herein illustrated as embodied in a press of the type commonly known as a clicking machine, such as that disclosed in United States Letters Patent No. 921,503 granted May 11, 1909 upon an application filed in the name of Arthur Bates, and illustrating a machine comprising a work-supporting bed, a reciprocating post, and a presser arm extending laterally from the post and movable therewith toward and away from the cutting bed to force dies through sheet material positioned upon the bed, thereby to form blanks.

This application is a continuation of application Serial No. 547,546, filed June 29, 1931, by this applicant and Donald G. McLean jointly, which issued as United States Letters Patent No. 2,021,138, on November 19, 1935 and is filed for the purpose of claiming herein subject-matter which was the sole invention of this applicant and which was inadvertently and erroneously claimed in said joint application. Other subject-matter disclosed but not claimed herein constitutes the subject-matter of the said joint application.

It is an object of the present invention to provide an improved machine of the type referred to, which, without sacrificing the characteristic advantages of such machines heretofore in use, will be so constructed and arranged that increased economy in the cutting of blanks will be effected and that the performance of operations by use of the machine will be facilitated.

To this end, the invention provides a machine of the type mentioned above having a frame, spaced supporting members mounted in the frame and presser members carried by the supporting members, in which the presser members have each a freely extending portion constructed and arranged to cooperate with the corresponding portion of the other presser member to produce a pressure-applying operation upon material positioned between the supporting members.

As illustrated, the presser members comprise a cutting bed and a presser arm supported at opposite sides of the frame, and have each freely extending portions relatively movable into overlapping position, the presser arm preferably being secured to a post mounted for reciprocation and rotation in the frame whereby the arm may be moved into operative position relatively to a die located upon the bed and can be forced toward and then away from the die to produce a pressure applying operation thereon. Preferably and as shown, the presser arm and cutting bed are so designed that the stiffness of each of them

increases from the free end thereof to the point of support. The illustrated arm and bed are so shaped in cross-section that the deflection of the arm at the point of application of pressure decreases as the pressure is applied closer to the axis of the post whereas the deflection of the bed at the point of application of the pressure increases under the same condition, the relative stiffness of the two members being such that for operations upon a die positioned at different points upon a cutting block forming part of the bed the total deflection of the arm and bed will be substantially the same with the result that the die is forced into the cutting block by substantially the same distance regardless of the position of the die upon the bed.

Machines constructed as above outlined are particularly effective because of the fact that the dieing-out operations performed by such a machine are more uniform in character which results in many advantages. For example, considerable economy is effected in the consumption of cutting blocks used in the machine for the reason that in resurfacing such a block it is necessary only to remove a small amount of material around the edges of the block which are not ordinarily touched by the die in the operation of the machine. Furthermore, in view of the fact that it is necessary only to trim the edges of the cutting block used in the present machine, the remaining central portions of the block provide a surface which is already broken in with the result that dieing-out operations can be performed more effectively and with less effort on the part of the operator than if an entirely fresh surface were provided.

In the present construction the die is forced into the block the same distance regardless of whether light or heavy material is operated upon and consequently the wear upon the block is uniform and the surface of the block is kept free from pockets. This is another reason why it is unnecessary to remove much material upon resurfacing. The elimination of pockets or soft places, particularly along the edges of the block, reduces the likelihood of breakage of dies resulting from the placing of a die with a portion thereof upon a comparatively high, hard surface at the edge of the block and another portion of the die upon a lower, softer portion of the block. In view of the fact that the machine operates to force the die into a block uniformly over all portions thereof, the penetration of the die into the block to produce the desired cut need not be very great. Consequently, there is little likelihood of the die becoming stuck in the block.

hood of a die becoming stuck in the block after a cutting operation. In view of this, also, considerable economy is effected in the use of dies, it being unnecessary to sharpen the edges of a die as frequently as would be the case if the die were forced deeply into the block. Likewise, since it is unnecessary to force a die deeply into the block to produce the desired results, the machine can be operated economically with regard to power used and the frame of the machine is subjected to less strain and vibration.

Other objects and features of the invention will be apparent from the following detailed description when taken in connection with the accompanying drawings and will be pointed out in the claims.

In the drawings,

Fig. 1 is a side elevation of a machine constituting one embodiment of the invention;

Fig. 2 is a front elevation of the machine with certain parts thereof shown in cross section;

Fig. 3 is a cross section taken along line III—III of Fig. 2 illustrating mechanism for adjusting the height of the bed; and

Figs. 4, 5, 6, and 7 are diagrammatic views illustrating the operation of the presser member and cutting bed.

As illustrated in Figs. 1 and 2 of the drawings, the machine comprises a C-shaped frame 10 upon one side of which is slidably mounted a hollow upright post 12 to which is secured a presser member or arm 14 arranged for cooperation with a second presser member, in the form of a cutting bed 16 mounted upon the opposite side of the frame, to apply pressure upon the bed. As is customary in machines of this type, the post 12 is movable angularly about its axis so that the presser arm 14 secured thereto can be moved over the bed 16 about the axis of the post, for example, into operative position relatively to a freely movable cutting die located upon the work. The post is arranged to be reciprocated vertically by a connecting rod 18 operatively connected to an eccentric 21 upon a rotary shaft 20 which is controlled by a one-revolution clutch 22 adapted to cause engagement of the shaft 20 with a flywheel 24. Reciprocation of the post 12 results in movement of the presser arm 14 toward and then away from the bed in a pressure-applying operation effective to force the die through the work to produce a blank.

The presser arm 14 comprises an integral casting located substantially entirely upon one side of the post 12 and secured thereto by clamping members 26. The arm extends freely over the central portions of the frame 10 and is of such length that it can be swung into a position in which its flat striking surface 28 overlies any desired portion of the cutting bed. The arm is so designed that its effective cross-section increases from its free end to a point near the axis of the post with the result that the stiffness of the arm under load increases as the point of application of the load upon the striking face 28 is brought closer to the axis of the post 12. Consequently, the maximum deflection of the arm under a given load upon the striking face 28 occurs when the load is applied to the extreme outer end of the arm, and the deflection is practically negligible when the same load is applied to the striking face near the axis of the post.

The body portion of the bed 16 comprises a casting having a flat cutting-block support 30 mounted upon a hollow column 32 which is slidably positioned in an enlarged portion 34 of the

frame 10. The frame portion 34 is provided with laterally extending ears 36 within which are located bushings 38 which support screw-shafts 40 extending upwardly substantially parallel to the axis of the column 32 and equally spaced laterally thereof. The upper portion of each of the shafts 40 is screw-threaded at 42 and engages a nut 44 secured by bolts 45 in an opening 46 in the under side of the bed 16, thereby supporting the bed in position above the frame. The support 30 carries a wooden cutting block 47 substantially co-extensive therewith and which is suitably secured thereto by bolts 48 (Fig. 1) which engage clamping irons 50 of the block. The forward portions of the bed 16 including the block 47 are located close to the plane of the axes of the screw-shafts 40, but the rearward portions of the bed extend freely toward the axis of the post 12 and overhang the central portions of the frame 10. Thus it will be seen that the forward portions of the bed are substantially rigidly supported against deflection during pressure-applying operations whereas the rearward or overhanging portions of the bed are less rigidly supported and are subject to deflection in a downward direction under pressure applied by the presser arm 14. The bed 16 is provided with stiffening ribs 52 which extend from the column 32 diagonally across the under side of the support 30 to the corners of the bed, and other ribs 54 (Fig. 1) extending from the ribs 52 toward the sides of the block. The ribs 52 and 54 are so constructed and arranged that the freely extending portion of the bed is stiffened substantially to an equal extent at points equidistant from the axis of the post 12, the effective cross-section of the bed increasing in thickness from the side of the bed nearest to the post to a maximum in the vicinity of the column 32. The bed is so designed relatively to the presser arm 14 that under load the bed remains substantially rigid when the yield of the arm is a maximum and yields increasingly as the arm stiffens, with the result that for a given stroke of the presser arm the pressure applied, for example, to a die supported on the cutting block 47 will be substantially constant for any position of the die upon the bed. For example, when a die is positioned upon the block 47 near the axis of the supporting column 32 and the presser arm is brought into position in which it overlaps the die and bed and is reciprocated, the arm is engaged near its outer end and, under load, is subjected substantially to its maximum deflection whereas the bed 16 remains substantially rigid. On the other hand, if a die is placed on the cutting block adjacent to its inner edge, the bed 16, under load, is subjected to substantially its maximum deflection whereas the presser arm 14 is engaged near the axis of the post 12 and consequently is subject to slight deflection only. Thus, for various positions of a die along the cutting bed at different distances from the axis of the post, the deflections under forces applied to the presser arm and bed during operation of the machine tend to balance each other, that is, the total displacement of the members engaging opposite sides of the die tends to remain constant. Furthermore, if a die is successively located on the cutting block at different points equidistant from the axis of the post, in which positions the die will be engaged by the same portion of the presser arm, the successive deflections of the bed and arm will be substantially the same. Consequently, the sum of the deflections of the portions of the arm and bed engaging the die will be sub- 75

stantially the same for any position of the die upon the cutting block. The pressure applied to the die and consequently the penetration of the die into the cutting block will therefore be substantially the same for all positions of the die on the block for a given position of the bed heightwise of the frame.

Means is provided for adjusting the bed 16 and cutting block 41 heightwise of the frame 10 or presser arm 14 whereby the depth of cut or penetration of the die into the block can be regulated. To this end, each of the screw-shafts 40 has secured thereto a gear 56 (Figs. 2 and 3) arranged to engage worms 58 and 59, respectively, which are secured to a horizontal shaft 60 arranged for rotation by a hand-wheel 62.

The shaft 60 extends through openings 64 in the frame portion 34 and through slots 66 in the column 32, the slots 66 being elongated to provide clearance for the shaft as the column is moved up or down with the bed. Rotation of the hand-wheel 62 in a counterclockwise direction results in a raising of the bed and the cutting block and vice versa.

To facilitate the handling of sheet material, the machine is provided with a trough 68 positioned upon the frame between the post 12 and the bed 16, the overhanging portion of the bed providing adequate clearance so that a considerable amount of material can be positioned in the trough out of the way of the operator who may operate upon a portion of the material which is drawn over the inner edges of the block 41 on to its upper surface, the material being conveniently held in position by a clamping device such as clamp 10.

The drive shaft 20 is arranged to be operatively connected at the will of the operator to a flywheel 24 (Figs. 1 and 2) driven by a motor 72 supported on the frame. The operative connection between the shaft and flywheel comprises a one-revolution clutch 22, for example, of the type illustrated in United States Letters Patent No. 1,011,903, granted December 19, 1911, upon an application filed in the name of Arthur Bates. The clutch 22 is operated by means of a handle 74 mounted on the presser arm 14 and arranged to engage a lever 76 which has a forked end 78 making engagement with a link 80 which is pivoted at 82 on the frame and has a rearwardly extending portion 84 to which is connected a link 86. The link 86 at its lower end is pivotally connected to a link 88 loosely carried on a stud 90 which in turn, carries a lever 92 which is operable to control the engagement of the clutch and flywheel in response to operation of the handle 74.

The operation of the various parts of the machine will be clear from the foregoing description. The operator places sheet material such as leather upon the cutting block 41 forming the upper part of the bed 16 and positions a die upon the work with the cutting edges of the die in contact with the work. The presser arm 14 is then swung about the axis of the post 12 until the striking face 28 of the arm is positioned over the die. The starting handle 74 is then depressed resulting in the engagement of the flywheel 24 with the shaft 20, thus causing a reciprocation of the post and presser member thereby to force the die through the work and into the cutting block. The operation of the presser arm 14 and the cutting bed 16 is illustrated in further detail by Figs. 4, 5, 6, and 7. These figures are diagrammatic only and very greatly

exaggerate the action of the various parts. The full lines in Figs. 4, 5, and 6 indicate the relative positions of the presser arm 14, the cutting bed 16 and a die 94 at the point in the cycle of operations of the presser member in which the striking face 28 of the presser member is in its lowermost position. In these figures the dotted lines indicated by reference characters 96 represent the position of the presser member 14 upon its initial engagement with the die in each case. Reference characters 98 in Figs. 4 and 5 indicate the position which the presser member would assume at the end of its stroke if the arm were not deflected due to resistance of the die to the movement of the member. Reference characters 100 indicate the normal position of the cutting bed 16 when it is not deflected under load. Reference characters 102 in Figs. 5 and 6 indicate the position of the cutting bed which it has taken as a result of deflection under load.

In the case illustrated in Fig. 4 it will be observed that the die 94 has been placed upon the cutting block in the vicinity of the axis of the column 32 in which case the resulting deflection of the bed is so small that it can be neglected. At the same time the presser arm 14 is engaged by the die close to its outer end in which case the amount of deflection of the arm represented by a is substantially at a maximum. This results in the forcing of the die into the cutting block by a slightly greater amount on the side of the die nearest the axis of the post. In Fig. 5 it will be observed that the die has been located centrally of the cutting block with the result that under load the bed has been deflected by an amount b whereas the arm 14 which engages the die a considerable distance inwardly of its end has been deflected by an amount a' . The deflections referred to are substantially equal and consequently the die has penetrated the cutting block to the same extent throughout the length of the die. In Fig. 6 the die has been placed on the cutting block near its inner edge portion, that is, near the axis of the post, and under load the bed has been deflected by a still greater amount b' but, since the die is engaged by the presser arm quite close to the axis of the post, the deflection of the arm is practically negligible. In view of the fact that the bed was deflected substantially to its maximum amount whereas the arm was not appreciably deflected, the penetration of the die will be slightly greater on the portion thereof away from the axis of the post. As illustrated by Fig. 7, letters c , d and e indicate the approximate position of the die 94 corresponding respectively to its positions shown in Figs. 4, 5, and 6, in which the die is shown in various positions along the central line of the block which passes through the axis of the post. The line 104 represents the central line of the presser arm 14 when it is swung laterally over the block to an angle of about 30° relatively to the central line of the block. If the die were placed successively at points c' , d' , and e' , which are located along the line 104 at the same distances from the axis of the post respectively as the points c , d , and e , the effect due to deflections of the arm and bed will be substantially the same as illustrated in Figs. 4, 5, and 6. For example, the deflection of the arm when the die is positioned at c' will be substantially the same as that when the die is positioned at c . Since the point c' is located a greater distance from the axis of the column 32 than the point c , it might be supposed that the deflection

of the bed would be substantially greater when the load is applied at c' . This is not the case, however, for the reason that the reinforcing ribs 52 serve to stiffen the bed in directions extending angularly of the central line of the cutting block. As a result of this, the deflection of the bed is approximately the same along an arc which has the axis of the post as a center, and, since a die positioned on the block anywhere along the arc engages the presser arm at the same point, the deflection of the arm will likewise be substantially the same with the result that the penetration of the die will be substantially uniform along said arc. In view of all this, it should be apparent that the compensating deflections of the presser arm and bed produced when the die is placed in different positions anywhere on the cutting-block surface will result in substantially the same penetration of the die into the cutting block for a given initial position of the bed heightwise of the arm.

In adjusting the height of the presser arm 14 for a die of given height, the arm is adjusted heightwise of the block through operation of the hand-wheel 62 and its associated mechanism into such position that at the end of the stroke of the presser member the die will be forced into the block a slight distance, in practice, from one-sixteenth to three-sixteenths of an inch. The presser arm will then be operative to perform cutting operations with the die in any position on the block and will be effective to perform such operations in a uniform manner over the entire surface of the cutting block.

Having described my invention, what I claim as new and desire to secure by Letters Patent of the United States is:

1. A machine for operating upon sheet material having a frame, and cantilever members constituting a presser member and a cutting bed mounted upon the frame for relative movement heightwise of each other and for movement relatively to each other into overlapping position in which the members extend in opposite directions from their points of support, wherein the successive cross sections of said members are of decreasing area outwardly from their points of support through substantially their entire lengths and wherein the cross sections of adjacent portions

of the members when the latter are in overlapping position are so related that the combined deflections of the members under a given load are substantially the same for applications of the load at different points along the lengths of the members. 5

2. A clicking machine comprising a frame, a cutting bed, means for supporting the cutting bed on the frame comprising an upright member the axis of which is located near one side of the bed, the bed being so constructed that it extends from 10 the upright member inwardly over a portion of the frame and out of contact therewith, a post slidably mounted in the frame, a presser arm secured to the post and having a free end arranged for movement across the cutting bed, and means for causing 15 relative movement between the presser arm and bed to produce a pressure applying operation upon work positioned upon the bed.

3. In a power driven clicking press a frame, a bed, a supporting column for the bed upstanding 20 at the front side of the frame, the bed extending further rearwardly than forwardly from said column, to such extent that the center of the bed is rearward of the center of the column by at least ten percent of the width of the bed, whereby the 25 bed tends to tilt yieldingly downward at its rear side under stress of operation, a presser swingable laterally over the bed, a supporting post for the presser at the rear side of the frame, and the presser extending forwardly therefrom with its 30 free end overhanging the bed, whereby the presser tends to tilt yieldingly upward at its front side under stress of operation, and power driven mechanism for depressing and raising the presser in each operation. 35

4. A machine for operating upon sheet material comprising a frame, a bed, a member carried by the frame and located at one side of the bed to support the bed with a portion thereof extending over the frame and spaced therefrom, a presser member mounted upon the frame and having a freely extending portion movable laterally over the bed, and means for causing relative movement of the bed and presser member to produce a pressure-applying operation upon material positioned between said portions. 40 45

MILTON H. BALLARD.
